DEVICE FOR APPLYING VISCOUS MATERIALS

William Rees, St. Louis, Mo.

Application February 19, 1940, Serial No. 319,670

3 Claims. (Cl. 91—39)

My invention has relation to improvements in devices for applying viscous materials such as liquid wax to surfaces that are to be polished, and it consists of the novel features of construction more fully set forth in the specification and pointed out in the claims.

The primary object of the invention is to associate the polishing accessories with the container for the liquid wax so that the wax will automatically exude from the container onto the polishing sponge or cloth instead of having to be periodically applied thereto. Of course the cloth is arranged so that it may be readily renewed and at the same time means are provided to prevent the liquid wax from flooding the cloth, it being essential that practically the entire surface of the cloth shall receive a proper infiltration of the liquid wax.

It is a further object of the invention to associate with the container for the liquid wax a roll of cloth or other suitable fabric which may be drawn on from time to time to renew the polishing surface of the device.

Another advantage of the invention is that it may be adapted for embodiment in the same container in which the liquid wax is marketed, said container being equipped with suitable securing devices for receiving the polishing accessories.

Other advantages will be better apparent from a detailed description of the invention in connection with the accompanying drawings, in which:

Figure 1 represents a side elevation of my improved wax applying device with parts broken away; Fig. 2 is a top plan of the device with parts broken away; Fig. 3 is a vertical cross-sectional detail taken on the line 3—3 of Fig. 1 and shown on an enlarged scale; Fig. 4 is a modification of the device in which a roll of polishing cloth is carried by the container and may be periodically unwound to renew the polishing surface of the device; Fig. 5 is a right hand end elevation of the device shown in Fig. 4; Fig. 6 is a left hand end elevation of said device; Fig. 7 is an enlarged sectional detail taken on the line 7—7 of Fig. 5, showing one end of the roll of cloth in plan view; Fig. 8 is a vertical sectional detail taken through the roll on the line 8—8 of Fig. 5; Fig. 9 is a top plan of a modified form of the invention in which the container in which the liquid wax is marketed is adapted for use in connection with the accessories for applying the wax for polishing; Fig. 10 is an enlarged vertical cross section taken on the line 10—10 of Fig. 9; Fig. 11 is an en-

larged vertical cross section taken on the line 11—11 of Fig. 9 with the intermediate parts broken away; and Fig. 12 is a bottom plan of the modified form of container shown in Fig. 9 with the accessories removed.

Referring to the drawings, and for the present to Figures 1 to 8 inclusive, I represents a metallic container in the top T of which is a threaded spout 2 adapted to receive the screw cap 3 and a threaded socket 4 for receiving a suitable handle 5. Also in the top T of the container I is a conventional form of air vent embodying a plate 6 secured to a handle 7 for rotation, in which plate is a slot 8 adapted for registration with slot 9 formed in the top T. It is possible that the air vent may be dispensed with and the cap 3 utilized for regulating the admission of air to the container I.

Container I is provided with a bottom wall 10 offset with respect to the bottom edges e, e of the side walls of the container, said bottom edges e being bent outwardly to provide lateral flanges f, f spaced from the side walls of the container I. These upwardly extending flanges f, f result in the formation of longitudinally extending grooves g, g, which serve to retain the polishing cloth in a manner presently to be described.

The bottom 10 of container I has a pair of spaced indentations 11, 11 over which are secured in any suitable manner perforated plates 12, 12. There is also a perforation 13 in the center of the indentation to permit the liquid wax to discharge into the chamber 14 formed between the indentation 11 and plate 12, from which it may discharge into a sponge or other form of previous pad 15 disposed over the entire bottom 10 of the container. The sponge 15 is held securely in place by a strip of cloth or other suitable fabric 16 securely held into grooves g, g by having its ends wrapped around wedges 17, 17 which are frictionally held within said grooves g, g.

In the modified form of the invention shown in Figures 4 to 8 inclusive the construction of the container I' is slightly different. A flange f' is provided only on one side of the container, there being an ordinary bead b on the other side, above which is mounted a roll R of cloth or other suitable fabric between a pair of brackets 18 and 19 fixed on the ends 20, 21 of the container. Bracket 18 is provided with a hub 22 above which extends an arm 23 having a detent 24 mounted in its extremity for engagement with the teeth of a ratchet wheel 25 fixed to spindle 26 which also carries roller 27 on which the sheet

28 of fabric is rolled. The bracket 19 is provided with a recess 29 to facilitate the mounting of the roll of fabric R in the brackets. It is obvious that when that portion of the cloth 28 beneath the pad 15' needs to be renewed the end thereof that is secured in the groove g' is removed and the fabric unrolled from the roller 27 until a new surface is exposed beneath the pad 15', after which the fabric is cut to the proper size and again wedged into groove g'.

In the operation of my improved device the container 1 (or 1') is supplied with liquid wax to any desired level x and the air vent 6 adjusted to permit the proper amount of air to enter the container so that the wax will flow through the opening 13 and through the perforated plate 12 in the proper amount to keep the pad 15 saturated, from which it will exude and penetrate the polishing cloth 16. Obviously, the operator can control the amount of wax that is forced from the pad 15 by the pressure with which the device is applied to the surface being polished as well as by the regulation of the vent 6.

In the modification shown in Figures 9 to 12 inclusive, the numeral 30 indicates a container in which the liquid wax is sold. In this container the top 31 is secured to the side walls 32, 32 by means of beads 33, 33 of substantial proportions so that they are capable of receiving and securely holding the handle plate 34 which is provided at one end with a hook 35 to engage one of the beads 33 and a spring clamp 36 for engagement with the opposite bead 33.

The bottom 37 of container 30 is depressed and is also secured to the side walls 32, 32 by means of beads 38, 38 of substantial proportions. The bottom 37 is provided with a pair of spaced indentations 39 in the center of each of which an opening 40 is formed when the container 30 is to be used for polishing operations. A bottom plate 41 is provided with marginal spring clamps 42, 42 of the proper shape to snap over the beads 38, 38 to hold said plate securely in place. There are two clusters of perforations 43 in the bottom plate 41 and spaced so as to come opposite to the indentation 39 in the bottom of container 30, and on both sides of each of said clusters of perforations there are openings 44, 44 which form pockets to receive any excess increments of the liquid wax that may otherwise have a tendency to flow between the bottom 37 of the container and the plate 41. A pad 45 similar to pad 15 is placed against plate 41 and projects beyond the lower margins thereof and a strip of cloth 46 is drawn

taut over the pad 45 to hold the same in place.

The strip of cloth 46 is itself held securely in place by wedges 47, 47 which engage the extremities of the cloth 46 and hold them securely within the grooves g'', g'' formed by the flanges f'', f'' extending upwardly from the spring clamps 42, 42. The means whereby the cloth 46 is securely held in place is identical with that illustrated in the main form, Figures 1 to 3 inclusive.

One of the advantages of the modified construction shown in Figures 9 to 12 inclusive is that the householder need have on hand only the accessories comprising the handle plate 34 and bottom plate 41, together with the pad 45 and cloth 46, which accessories are adapted to be secured to the container 30 when the same is purchased containing the liquid wax.

Having described my invention, I claim:

- 20 1. A device for applying viscid liquids comprising a container having a discharge opening in the bottom thereof, an absorbent pad disposed over said opening, a polishing fabric drawn taut over the pad, clamping devices arranged at the sides of the container, and wedges cooperating with the clamping devices to engage the fabric and hold the same in place.
- 25 2. A device for applying viscid liquids comprising a container having oppositely disposed upper and lower beaded edges, a bottom plate having marginal spring clamp formations engaging the bottom beaded edges, the bottom of the container having an indentation forming a liquid receiving chamber with said bottom plate, liquid escape passageways in said bottom plate, an absorbent pad disposed over the bottom plate, a polishing fabric drawn taut over said pad, means on the plate engaging the fabric and holding same in place, and a handle plate having spring clamps engaging the upper beaded edges of the container.
- 30 3. A device for applying viscid liquids comprising a container having oppositely disposed lower beaded edges, a bottom plate having marginal spring clamp formations engaging said beaded edges, the bottom of the container having a perforated indentation forming a liquid receiving chamber with said bottom plate, liquid escape passageways in said bottom plate, an absorbent pad disposed over the bottom plate, a polishing fabric drawn taut over said pad, and means on the plate engaging the fabric and holding the same in place.

WILLIAM REES.
